UNITED STATES PATENT OFFICE.

HENRY L. BRADLEY, DECEASED, LATE OF NEW HAVEN, CONNECTICUT, BY BESSIE LEE BRADLEY, EXECUTRIX, OF NEW HAVEN, CONNECTICUT, ASSIGNOR TO THE ATLAS MANUFACTURING COMPANY, OF NEW HAVEN, CONNECTICUT, A CORPORATION.

HINGE-BUTT.

1,053,900.

Specification of Letters Patent.

Patented Feb. 18, 1913.

Application filed May 4, 1912. Serial No. 695,161.

To all whom it may concern:

Be it known that HENRY L. BRADLEY, deceased, formerly a citizen of the United States, residing at New Haven, in the 5 county of New Haven and State of Connecticut, (BESSIE LEE BRADLEY, executrix,) did invent a new and useful Improvement 10 in Hinge-Butts; and it is hereby declared that the following, when taken in connection with the accompanying drawings and the characters of reference marked thereon, is a full, clear, and exact description of the same, and which said drawings constitute part of this application, and 15 represent, in—

Figure 1 a face view of a hinge butt constructed in accordance with this invention, and shown in the open position. Fig. 2 a side view of the same, closed. Fig. 3 an 20 edge view. Fig. 4 an inside view of one of the leaves. Fig. 5 an inside view of the other leaf.

This invention relates to an improvement 25 in hinge butts, the object being to produce the butts from sheet metal whereby the labor of mortising the butt in the jamb and in the door will be reduced, and in which the strain will be partially taken from the screws; and the invention consists in the construction 30 hereinafter described and particularly recited in the claims.

In carrying out the invention, the butt, like usual butts, comprises two leaves. As herein shown, the left hand leaf consists of 35 two arms 2, 3. These arms are struck from sheet-metal their inner ends being rolled to form knuckles 4, 5, the ends of which are flared outward forming flanges 6. The right hand leaf comprises two arms 7, 8. 40 These arms are duplicates of the arms 2, 3; that is, the upper arm 7 at the right is a duplicate of the lower arm 3 at the left; and the lower arm 3 at the left is a duplicate of the upper arm 2 at the right. These 45 arms 7 and 8 are likewise formed with knuckles 9 and 10. The two arms 2 and 3

are connected together by a short plate 11 which may be riveted, brazed or otherwise secured to the arm so as to be firmly interlocked therewith; and the arms 7 and 8 are 50 likewise connected by a bar or strap 12. The knuckles receive the usual pin 13 by which the two leaves are connected together, and at the bottom is the usual ornamental knob or acorn 14. It will be noted that the 55 bar 12 stands below the surface of the arms 7 and 8 and so that the arms 2 and 3 when the butt is closed, will bear against this bar and bring the face of one leaf into line with the face of the other leaf. As before stated, 60 these leaves are struck up from sheet metal and are formed with inwardly extending flanges 15, and the arms are provided with the usual screw holes 16 more or less in number. These flanges 15 being compar- 65 atively sharp owing to the fact that the leaves are formed from sheet metal, may readily be embedded in the door jamb and edge of the door, and thus avoid the necessity of mortising both the door and the 70 door jamb. To facilitate mortising, however, when applied to hard woods the ends of the arms form segments of circles so that the ends of the mortise may be readily formed with an auger. The flanges 75 strengthen the arms and by being embedded in the wood take a portion of the strain which usually comes upon the screws.

It is apparent, without illustration, that the leaves of the hinge might be formed in- 80 integral, that is, the arms 2 and 3 might be formed from a single piece of metal and the arms 7 and 8 from one piece of metal; but for convenience in manufacture they will be formed separately. By rolling the knuckles 85 the metal is strengthened, and by turning out the flanges the knuckles are likewise strengthened and sufficient bearing surface provided between them to provide the necessary strength. The straps 11 and 12, if 90 made of proper width, may serve as guides in applying the butts.

Claim:—

A hinge butt the leaves of which each comprise two outwardly extending reversely turned, separately formed arms, 5 each arm having an integral knuckle, a pin extending through said knuckles, and a bar connecting the arms of each leaf.

In testimony whereof, I have signed this

specification in the presence of two subscribing witnesses.

BESSIE LEE BRADLEY,
Executrix of Henry L. Bradley, deceased.
